ATTORNEY

UNITED STATES PATENT OFFICE.

ALEX MARCUS, OF BROOKLYN, NEW YORK.

DESIGN FOR A POWDER-PUFF.

55,392.

Specification for Design.

Patented June 1, 1920.

Application filed March 12, 1919. Serial No. 282,216. Term of patent 14 years.

To all whom it may concern:

Be it known that I, ALEX MARCUS, a citizen of the United States, residing at Brooklyn, in the county of Kings and State of New York, have invented a new, original, and ornamental Design for a Powder-Puff, of which the following is a specification, reference being had to the accompanying drawings, forming a part thereof, and in which:

Figure 1 is a top view, and
Fig. 2 an edge view of a powder puff
embodying my design.

I claim:

The ornamental design for a powder puff,
as shown.

ALEX MARCUS.
